UNITED STATES PATENT OFFICE.

ERNST FRIEDERICH, OF BERLIN, GERMANY, ASSIGNOR, BY MESNE ASSIGNMENTS, TO
GENERAL ELECTRIC COMPANY, OF SCHENECTADY, NEW YORK, A CORPORATION OF
NEW YORK.

ELECTRIC LAMP.

Application filed August 30, 1921. Serial No. 496,942.

(GRANTED UNDER THE PROVISIONS OF THE ACT OF MARCH 3, 1921, 41 STAT. L., 1313.)

To all whom it may concern:

Be it known that I, ERNST FRIEDERICH, a citizen of Germany, residing at Berlin, Germany, have invented certain new and useful Improvements in Electric Lamps (for which applications for patents have been filed in Germany, June 3, 1914, A26055, VIII/21f, and August 13, 1914, A26383, VIII/21f; Hungary, May 22, 1915, and 10 August 13, 1915; Switzerland, May 22, 1915, and August 10, 1915; Netherlands, May 28, 1921, and August 10, 1915; Sweden, June 2, 1915, and August 11, 1915; Great Britain, June 3, 1915, and August 12, 1915; Japan, 15 March 4, 1920, and March 11, 1920; Austria, May 31, 1915, and August 23, 1915), of which the following is a specification.

The present invention relates to electric lighting, and more particularly to a lamp 20 in which an arc is operated in an enclosed envelope between electrodes of highly refractory metal, such as tungsten surrounded by an inert gas or vapor, and so proportioned that they will be heated to incandescence.

One of the objects of my invention is to provide means for starting the arc in a lamp 25 of this nature. A further object of my invention is to provide an improved arrangement of electrodes whereby a higher operating efficiency, a longer life and a better light distribution may be obtained.

The novel features of my invention with further objects and advantages will best be understood by reference to the following description taken in connection with the accompanying drawing in which Fig. 1 illustrates a lamp equipped with one of my improved starting devices; Fig. 2 shows a modification thereof in which two sets of electrodes are connected in series and in which electrodes of an improved form are employed; Fig. 3 is a view of the supporting arrangement for the electrodes of the lamp shown in Fig. 2 taken at a right angle to the view indicated in Fig. 2; Fig. 4 is a bottom view of the arrangement used in Fig. 2 for starting the lamp; and Fig. 5 is an enlarged detail view of one pair of the electrodes of the lamp shown in Fig. 2 with the starting conductor which bridges them when the lamp is not in operation. Fig. 6 is a

wiring diagram of the arrangement shown in Fig. 2.

Difficulty has been experienced in starting the arc in lamps of this nature because of the fact that a higher voltage is required to bridge the gap between the electrodes to start the arc than is required for its normal operation. Neither can the arc be readily started by bringing the electrodes in contact with each other and then separating them. I have found, however, that it is comparatively easy to start such lamps by removing an intermediate conducting member which bridges the electrodes when the lamp is not in operation, provided a suitable material is used for this bridging member. Among the materials which may be used for this purpose are metals which have a higher electronic emission than tungsten at the same temperature, such as copper, zinc, or even metalloids such as carbon, boron, silicon or the like. Another class of materials which are more suitable are oxides which are good conductors when cold, such as uranium oxide, vanadium oxide and the like.

The method of operation of my improved starting device may perhaps be explained 30 as follows:

Of the conductive bridging member some portion, though very small, will cling to the refractory electrodes by the mechanical pressure of the contact or by fritting, as soon as the part which is in contact becomes heated by its resistance when the circuit is closed. At these particles the arc starts and easily persists in consequence of the suitability of the material. These small particles of course are vaporized rapidly but in the meantime the temperature of the electrodes has risen so rapidly that they themselves now maintain the arc continuously and reliably. With respect to the conducting oxides it is possible that the suitability of such materials may for my purpose be explained by the well-known phenomenon that such oxides as soon as they become heated emit large numbers of electrons and on this account reduce to a large extent the voltage drop across the electrodes. The conductive uranium oxide having a formula UO_2 is particularly well adapted for the present pur-

pose. This can easily be made in the form of plates, bars and the like by pressing the oxide powder and baking in a hydrogen atmosphere at about 1600° C. A mixture of 5 uranium oxide with powdered tungsten is even better than the pure uranium oxide. It may in some cases be possible to use even oxides which are not conducting by mixing them with other conductive materials, such 10 as tungsten. Under some circumstances even it may be advantageous not to mix the conducting and non-conducting materials as powder and employ them in the form of homogeneous bodies, but to employ two superposed plates of the two materials. In this case the conductive member produces 15 the contact and when this is removed the second plate exerts the same action as readily fusible metals or conducting oxides. In the 20 preferred form of my starting device the conducting bridging piece touches the two electrodes and is automatically removed from them by an electromagnet when current passes. The movement of this bridging 25 piece may, however, be effected in any other suitable manner.

In the embodiment of my invention shown in Fig. 1 the lamp 1 comprises two electrodes 2, 3, of refractory metal, preferably 20 tungsten enclosed in an exhausted receptacle and connected with the supply conductors 4, 5. A bridging member 6 which in this case is made in the form of a wedge normally rests upon the electrodes 2, 3, and is connected to the iron core 7. This iron core 35 is adapted to move in a suitable guide in the lamp base. As soon as current starts to flow through the lamp the coil 8 which is in series with the supply conductor 5 causes the iron core 7 to rise and lift the 40 bridging piece 6 out of contact with the electrodes. This causes the arc to start and as long as it continues the bridging member 6 will be held up out of contact with the 45 electrodes.

In the forms shown in Figs. 2 to 5 two pairs of electrodes are connected in series between the supply conductors. Each of these pairs comprises a small ball 9 which 50 serves as cathode and a larger ball 10 which serves as anode. In this case the bridging piece 11 is of cylindrical form with flanges 12 at each end. The electrodes are supported by small wires 13, 14. In order to insure 55 a good contact between the bridging member 11 and the electrodes this piece is guided by the stem 14 of the anode. The under side of the bridging member also has a hollow portion 15 which rests directly 60 upon the anode 10. By this arrangement the center of the smaller cathode 9 may be located at the same height as that of the anode 10. The means for raising the bridging members from the electrodes comprise 65 two wires 16, having forked ends which

loosely engage the bridging members 11, which are sealed into a small glass bead 17. This bead is carried by the stem 18 which is connected to the armature 19 of a solenoid. This solenoid, which is not shown, 70 may be arranged in the lamp base and connected in series with one of the supply wires. The method of operation of this form of my invention is the same as that of the form indicated in Fig. 1. At the point where the 75 stem 18 passes through the flattened portion of the lamp stem, it is of advantage to insert a small tube 20 to serve as a guide for the stem 18. I also find it desirable to provide a spring 21 around the stem 18 below the armature 19 in order to break the force of the blow upon the electrodes when the bridging member is released.

In lamps of this type it has been observed that the cathode becomes less heated and accordingly radiates less light than the anode. In order to equalize this difference, I have indicated in Fig. 2 a cathode which is much smaller than the anode. In this case the light radiating surface of the cathode has 80 been made smaller than would be necessary to cause them to operate at the same temperature so that in the operation of the lamp the temperature of the cathode is higher 85 than that of the anode. This is of advantage for several reasons. It has been shown in lamps of this type that the anode always becomes smaller in the course of operation by reason of loss of material while the cathode always increases in size. The cause of 90 this is probably that particles of the material of the anode are positively charged and are carried from the anode to the cathode. At the cathode either no vaporization at all takes place or else the material 95 which is vaporized is continuously replaced from the anode. These phenomena which result in a variation of the intensity of the light and its efficiency may be overcome by reducing the radiating surface of the 100 cathode as I have indicated. It has even been found practicable to make the ratio of the surface of the cathode to that of the anode as low as 1 to 10. The current intensity 105 may be selected so that the anode will operate at the normal efficiency in lamps of this type and the cathode will operate at a much higher efficiency. In addition to the increase in total efficiency which may be secured in this way, there is the further 110 advantage that the lamp can be made of a smaller candle power and that it burns much more quietly and steadily, and less regulating resistance is needed than in the 115 case of a lamp having two electrodes of 120 the same size. If the electrodes are properly proportioned a constant intensity of light can be obtained, that is, the decrease in 125 light radiation from the cathode in consequence of its increase in size may be made 130

to just balance the increase in radiation from the anode by reason of its reduction in size. Reducing the size of the cathode in comparison with that of the anode has 5 still another advantage. In lighting lamps of this nature it is necessary that the cathode shall first be heated to a high temperature. If the cathode is of small area in comparison with the anode and the lamp 10 is to be started by bringing the electrodes in contact and withdrawing them, the cathode will become more highly heated at the contact point by reason of its small size and higher resistance, and on this account it 15 becomes possible to start the arc by merely bringing the electrodes together and separating them. This advantage is also present when the lamp is lighted by the use of an auxiliary electrode or if it is to be lighted 20 by removing a bridging member as heretofore described.

It will of course be understood that the method of starting which I have described is in no way limited to spherical electrodes 25 as other forms of electrodes, helical for example, may equally well be employed. It will also be apparent that many variations may be made in the particular arrangement used for withdrawing the bridging member 30 from contact with the electrodes.

What I claim as new and desire to secure by Letters Patent of the United States, is,—

1. In an electric lamp, the combination 35 of a sealed envelope having therein electrodes of highly refractory metal separated by a short gap and so proportioned as to be heated to incandescence by the passage of an arc between them, the surface area of the electrode which serves as a cathode being 40 so small with respect to that of the anode that when the lamp is in operation the temperature of the cathode is maintained higher than that of the anode.

2. An electric lamp comprising a sealed envelope having therein spherical electrodes of highly refractory metal separated by a short gap and so proportioned as to be heated to incandescence by the passage of an arc between them, the electrode which 50 serves as a cathode being larger than the one which serves as anode whereby when the lamp is in operation the temperature of the cathode is maintained higher than that of the anode.

3. An electric lamp comprising a sealed envelope having therein spherical electrodes of highly refractory metal separated by a short gap and so proportioned as to be heated to incandescence by the passage of an arc between them, the electrode which 60 serves as a cathode being larger than the one which serves as anode, whereby when the lamp is in operation the temperature of the cathode is maintained higher than that

of the anode, and means for starting an arc between said electrodes comprising a body of conducting material which bridges said electrodes when the lamp is not in operation and which is automatically withdrawn from 70 said bridging position when current starts to flow in said lamp.

4. In an arc lamp a sealed envelope, a pair of electrodes of solid refractory metal adapted to be connected to a source of current, said electrodes separated by a gap, a solid arc starting element bridging the gap and being in contact with the two electrodes before the arc is established and electromagnetic means for separating the element 80 from the electrodes for establishing the arc between the electrodes and for holding the element from across the gap as long as the arc is established, the surface of said element having a higher electronic emission 85 than the metal at the same temperature whereby the arc may be established at a lower voltage than when the electrodes are brought into contact directly.

5. In an arc lamp a sealed envelope, a 90 pair of electrodes of refractory solid metal adapted to be connected to a source of current, said electrodes separated by a gap, an arc starting element forming contact with the electrodes and bridging the gap, electromagnetic means for starting the arc between the electrodes by withdrawing the element 95 from across the electrodes and for maintaining the element out of engagement with the electrodes while the arc is in operation. said element being in the form of a solid the surface of which is adapted to yield an electronic emission sufficient to start the arc between the electrode at a lower voltage 100 than if the electrodes are brought into contact directly and separated, said envelope containing a gas which is inert with respect to the electrode.

6. In an arc lamp a sealed envelope, a 110 pair of electrodes of tungsten adapted to be connected to a source of current, said electrodes separated by a gap, a solid arc starting element bridging the gap and being in contact with the two electrodes before the arc is established and electromagnetic means for separating the element from the electrodes for establishing the arc between the electrodes and for holding the element from across the gap as long as the arc is established, the surface of said element having a 115 higher electronic emission than the metal at the same temperature whereby the arc may be established at a lower voltage than when the electrodes are brought into contact directly.

7. In an arc lamp a sealed envelope, a pair of electrodes of tungsten adapted to be connected to a source of current, said electrodes separated by a gap, an arc starting element forming contact with the elec- 120 125

trodes and bridging the gap, electromagnetic means for starting the arc between the electrodes by withdrawing the element from across the electrodes and for maintaining the element out of engagement with the electrodes while the arc is in operation, said element being in the form of a solid the surface of which is adapted to yield an electronic emission sufficient to start the arc be-

tween the electrode at a lower voltage than 10 if the electrodes are brought into contact directly and separated, said envelope containing a gas which is inert with respect to the electrode.

In testimony whereof I affix my signature.

ERNST FRIEDERICH.
